DISPLAY STAND FOR A MODEL AIRPLANE

John A. Dey, Coral Gables, Fla.

Application June 25, 1954, Serial No. 31,180

Term of patent 14 years

(Cl. D34—15)

Fig. 1

Fig. 2

To all whom it may concern:

Be it known that I, John A. Dey, a resident of Coral Gables in the county of Dade, in the State of Florida, have invented a new, original, and ornamental Design for a Display Stand for a Model Airplane, of which the following is a specification, reference being had to the accompanying drawing, forming a part hereof.

Fig. 1 is a top plan view of a display stand for a model airplane showing my new design; and

Fig. 2 is a side elevational view thereof.

I claim:

The ornamental design for a display stand for a model airplane, as shown.
